BOOK COMPANY, LIMITED, OF TORONTO, ONTARIO, CANADA, A CORPORATION OF
ONTARIO

MANIFOLDING BOOK

Application filed April 7, 1928. Serial No. 630,580.

This invention relates to an improvement in manifolding books and with respect to its more specific features to four-copy books.

An object of the invention is to provide a manifolding book wherein four copies may be simultaneously made, three of which are opaque, one adapted to be retained in the book, and the others removed.

Another object is to provide a book of the character specified, wherein the four copies may be simultaneously made by means of one single faced transfer leaf and one double faced transfer leaf.

Another object is to provide in a book of the character specified, a pad composed of sets of three leaves, one bound and the others supported by the bound leaf, one of the others being translucent and interposed between the remaining leaves of the set.

Other objects of the invention will be in part obvious and will in part appear hereinafter.

The invention accordingly comprises an article of manufacture possessing the features, properties, and the relation of elements which will be exemplified in the article hereinafter described and the scope of the application of which will be indicated in the claim.

For a fuller understanding of the nature and objects of the invention reference should be had to the following detailed description taken in connection with the accompanying drawing, in which:

Figure 1 is a perspective view of an embodiment of the invention, with parts broken away,

Fig. 2 is a similar view of an alternate arrangement.

In the embodiment of the invention shown in Fig. 1, the improved book is composed of pads, one of which comprises a series of leaves 1, which is bound to a backing 2, as for instance manila board, in any suitable manner, in the present instance by staples 3. The leaves 1 are opaque, and on the upper side of each leaf there is provided any suitable form indicated at 4, and in use, the leaves 1 are the originals of the record.

A second backing 5 is hinged to the end

of the backing 2 remote from the binding 3, by a flexible strip 6, in such manner that the backing 5 may fold onto the backing 2 as shown. The second pad is connected to the backing 5, and this pad is composed of a plurality of sets of record leaves, each set including a leaf 7 bound at one end, a leaf 8 carried by the leaf 7 at the other end, and a leaf 8^a carried by the leaf 8. All of the leaves 7 of the sets are bound together at that end of the backing 5 remote from the hinge 6, the binding in the present instance being by means of staples 9, although it is obvious that any other form of binding might be used. The leaves 7 and 8 are integral, and are opaque, but the leaf 8^a is of tissue, and is pasted to the underside of the leaf 8. In the present instance it is connected to the leaf 8 at the end remote from the connection of the leaf 8 with the leaf 7 by a line of paste.

A plurality of transfer leaves 10 and 11 is supported by the second pad, the transfer leaves in the present instance being bound with the leaves 7 of the sets, and the transfer leaves are so arranged that the leaf 11 may be interposed between the leaves 7 and 8^a of the sets, while the leaf 10 may be interposed between the leaves 1 and the leaves 8 of the sets. The leaves 1 are intended to be retained in the book as a permanent record, and as each leaf is used, it is placed beneath the second pad, occupying a position between the backings 2 and 5, as clearly shown in Fig. 1. In order to insert a leaf 1 beneath the second pad, the said pad is swung away from the first pad on the hinge 6, and the leaf 1 is permitted to fall into place on the backing, after which the second pad is returned to the position shown. As before stated, the leaves 1 are designed to be retained in the book as a permanent record, but the sets are intended to be removed from the book. Hence each leaf 7 is provided with a weakened line 12 near the binding, and a weakened line 13 is provided between the leaves 7 and 8 of the sets, the weakened lines being in the present instance lines of partial separation. The transfer leaf 11 is double faced, so that an impression will be made on the obverse side of the leaf 8^a, which

will be visible through the leaf. The transfer leaf 11 also carries the impression to the leaf 7, and the transfer leaf 10 carries the impression to the leaf 8. When not in use, 5 all of the leaves 1 are folded down upon the second pad. When in use, all of the leaves 1 except the lowermost are turned back into the position of Fig. 1.

In the embodiment of the invention shown 10 in Fig. 2, the construction is precisely the same as that shown in Fig. 1, with the exception of the arrangement of the translucent leaf, that is the leaf corresponding to the leaf 8^a of Fig. 1. Referring to Fig. 2, it will 15 be seen that the leaf 14 corresponding to the leaf 8^a of Fig. 1, is secured to the leaf 15 which corresponds to the leaf 8 of Fig. 1, near its connection with the leaf 16 corresponding to the leaf 7 of Fig. 1. The second pad comprises the leaves 14, 15 and 16, the leaf 14 being carried by the leaf 15, while the leaves 15 and 16 are integral. The book is used in 20 precisely the same manner, the lowermost transfer leaf 17 of the leaves 17—19 being interposed between the leaves 14 and 16, while the transfer leaf 19 is interposed between the leaf 18 and the leaf 15 of the first pad, corresponding to the leaves 1 of Fig. 1, and the sets.

30 Since certain changes may be made in the above article and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters 35 Patent, is:

40 A manifolding book comprising in combination, two pads of leaves so arranged that the leaves of one pad may be superposed upon the leaves of the other pad, the leaves of one 45 pad being arranged in sets of three leaves, one bound and the others supported by the bound leaf at the end remote from the binding, and transfer leaves supported by said pad and relatively positioned with reference 50 to the pads so as to be interposed between the leaves of the sets and between the sets and the leaves of the other pad.

In testimony whereof I affix my signature.
EDWARD KIRBY BOTTLE.
